UNITED STATES PATENT OFFICE.

MILETUS J. WINE, OF WASHINGTON, DISTRICT OF COLUMBIA.

FILE-BOX.

SPECIFICATION forming part of Letters Patent No. 290,616, dated December 18, 1883.

Application filed June 23, 1883. (No model.)

To all whom it may concern:

Be it known that I, MILETUS J. WINE, of Washington, in the District of Columbia, have invented certain Improvements in File-Boxes, 5 of which the following is a specification.

This invention relates to an improved follower or pressure device intended for use in those drawers or trays which, standing normally in a horizontal or substantially horizontal 10 position, are employed for filing or retaining papers, drawings, or other sheets, the aim of the invention being to provide a simple and automatic device by which the papers may be retained under a suitable degree of compression, and which will admit of papers being examined and removed with facility.

To this end it consists in a combination, with the drawer or other holder, of a weighted follower-plate hinged at one edge to a transverse 20 bar, which is in turn hinged or pivoted at the outer or lower end of the tray, as hereinafter more fully explained.

I have represented my invention in connection with that class of drawers or trays which 25 are arranged to remain in an inclined position when withdrawn from the case or cabinet. It may be applied with equal facility to those of other styles.

Referring to the accompanying drawings, 30 Figure 1 is a perspective view, illustrating three open drawers or trays with my improved device attached, the device being represented in the different positions in the respective drawers. Figs. 2, 3, and 4 are vertical longitudinal sections through one of the drawers, showing the follower in its various positions. Fig. 5 is a vertical cross-section on the line α - α of Fig. 2, showing the sliding connection of 35 the pressure-bar. Fig. 6 is a face view of one of the plates by which said bar is sustained.

Referring to the drawings, A represents the case or cabinet, and B the drawers or trays mounted therein.

In applying my improvement I provide for 45 each tray a flat follower - sheet, C, of sheet metal, pasteboard, or equivalent material, and of a size somewhat smaller than the interior of the drawer. At its forward edge I hinge the follower to a transverse gravitating-bar, 50 D, arranged to extend across the tray from side

to side, this bar being in turn secured to the tray at its forward edge by a jointed connection, which admits of its swinging forward and backward. It is preferred to have the jointed connection, by which the bar is retained in 55 place, of such character, as shown in the drawings, that it will admit of the bar rising and falling bodily within the drawer; but this is not a necessary feature.

The connection employed for the bar consists of two vertically-slotted plates, E, secured to the inner faces or sides of the drawer on opposite sides and of necks or spindles extended outward from the ends of the bar D through the slotted plates, and provided on their outer 60 ends with heads or washers a , by which their escape is prevented. This connection admits of the bar D rising and falling freely within the drawer, and also admits of its being turned backward or outward when elevated to the top 70 of the drawer, as shown in Figs. 1 and 4.

The bar D is preferably made of metal or suitably weighted, in order that it may rest with a considerable degree of force upon the papers within the drawer, so that the same 75 may be retained at their lower or forward edges when the follower is raised. The follower C is also made of suitable weight, or provided, as shown, with a weight, b , secured firmly to its free end, whereby it is also caused 80 to bear upon the papers with a moderate degree of pressure.

In making use of the device, the papers are placed within the drawer, and the bar and follower-plate turned inward and permitted to 85 rest upon them in the manner represented in Fig. 2 and on the left hand in Fig. 1. In this position of the parts the papers are subjected to a sufficient pressure to keep them in a flat and compact condition, while their upper 90 edges, being exposed above the edge of the follower-plate C, may be readily turned upward to examine the inscriptions thereon without the necessity of lifting the plate.

In order to gain access to the body portion 95 of the papers while retaining them in position, it is only necessary to turn the follower C outward or forward upon its hinges in the manner represented in Fig. 3, and in the upper drawer of Fig. 1. When the parts are in this 100

position, it will be observed that the bar D continues to bear upon and confine the forward edges of the sheets, while the upper portions are left entirely free, so that they may be turned or folded forward. If, however, it be desired to have access to the entire face of the sheets, or to remove the sheets from or add others to the number in the drawer, the follower is lifted so as to bring the bar D to the top of the drawer, and then turned outward and permitted to hang in the position represented in Fig. 4, and on the righthand of Fig. 1, the bar D being in such case reversed, so as to bear upon the front edge of the drawer, 15 while the follower-plate hangs in a pendent position therefrom. To permit the convenient manipulation of the follower-plate, it will be provided with a knob, as shown, or with a handle or other equivalent device.

20 While the slotted plates represented in the drawings constitute a simple and efficient connection between the bar and the tray, it is to be understood that any equivalent connection which will permit a free rising and falling motion of said bar, and also a rolling motion of the same may be substituted.

Although I have described above and have illustrated in the drawings weights of considerable thickness applied to the follower-plate, 25 and provided with knobs or handles as a means

for lifting the same, I propose to omit the knobs, when desired, and to extend the weight in a thin, flat form, in order to reduce its vertical thickness, and thus render the tray practically available to its full capacity. 35

Having thus described my invention, what I claim is—

1. In combination with a tray or drawer, a transverse gravitating bar, and a joint, substantially as described, connecting said bar at 40 one edge with the tray, said parts adapted, as described, to permit the bar to rise and fall freely, and also to permit the same to be turned backward from the end of the tray, as described.

2. In combination with a drawer or tray for papers, a transverse gravitating bar jointed at one edge to the end of the said receptacle and arranged to swing outward at the top, as described, and the weight or pressure-plate having one edge hinged to said bar and the opposite end free to rise and fall, as described. 45

3. In combination with the drawer or receptacle, the vertical slotted plates, the transverse bar having its journals seated in said plates, and the weighted follower C, hinged at 55 one edge to said bar.

MILETUS J. WINE.
